CLAIM

The ornamental design for a combined chain and coupler for a chain wrench, as shown and described.

DESCRIPTION

FIG. 1 is a perspective view of a combined chain and coupler for a chain wrench showing my new design;

FIG. 2 is a front view thereof;

FIG. 3 is a right side view thereof;

FIG. 4 is a back view thereof; and,

FIG. 5 is a top view thereof;

FIG. 6 is a left side view thereof;

FIG. 7 is a bottom view thereof;

FIG. 8 is a right side view thereof shown in a first alternate moved configuration;

FIG. 9 is a right side view thereof shown in a second alternate moved configuration;

FIG. 10 is a right side view thereof shown in a third alternate moved configuration;

FIG. 11 is a right side view thereof shown in a fourth alternate moved configuration; and,

FIG. 12 is a right side view thereof shown in a fifth alternate moved configuration.
